UNITED STATES PATENT OFFICE

106,001

DESIGN FOR A SADIRON OR SIMILAR ARTICLE

Howard A. Smith, St. Louis, Mo., assignor to Knopp-Monarch Company, St. Louis, Mo., a corporation of Missouri

Application January 12, 1937, Serial No. 67,019

Term of patent 7 years

To all whom it may concern:

Be it known that I, Howard A. Smith, a citizen of the United States and a resident of the city of St. Louis and State of Missouri, have invented a new, original, and ornamental Design for a Sadiron or Similar Article, of which the following is a specification, reference being had to the accompanying drawing, forming part thereof.

I claim:

The ornamental design for sadiron or similar article as shown and described.

HOWARD A. SMITH.

CERTIFICATE OF CORRECTION.

Design No. 106,001.

September 7, 1937.

HOWARD A. SMITH.

It is hereby certified that the name of the assignee in the above numbered patent was erroneously described and specified as "Knopp-Monarch Company" whereas said name should have been described and specified as Knapp-Monarch Company, of St. Louis, Missouri, a corporation of Missouri, as shown by the records of assignments in this office, and that the said Letters Patent should be read with this correction therein that the same may conform to the record of the case in the Patent Office.

Signed and sealed this 19th day of October, A. D. 1937.

Henry Van Arsdale.
